UNITED STATES PATENT OFFICE.

CHARLES HERBERT CANFIELD, OF SYRACUSE, NEW YORK.

CLOTHES POUNDER.

Application filed October 28, 1926. Serial No. 144,781.

This invention relates to clothes washing apparatus, particularly to pounders of the suction cup type, and has for its object the provision of a novel manually operable 5 clothes pounder adapted to be engaged upon any ordinary tub or similar receptacle for the purpose of pounding the clothes immersed in suitable suds.

It is well known that probably the most 10 efficient method of washing clothes is to force air and water through them while keeping them in a state of agitation. The broad principle involved in the employment of suction cup pounders is generally understood 15 as it is known that when an inverted cup member is brought forcibly into engagement with clothes immersed in suds or the like the compressing effect causes the air within the cup to pass through the clothes, and that 20 when the compressing effect is relieved there is a vacuum forming tendency which sucks water through the clothes, all dirt being effectively loosened and removed.

It is with the above broad principle in view 25 that I have designed the present invention which has for an object the provision of a washing device which may be clamped upon the side of a tub and in which the moving parts may be swung horizontally so as to 30 bring the cup into engagement with all the clothes being washed instead of it operating only at one very limited area.

An important object of the invention is to 35 provide a device for this purpose embodying a cup which acts as the pounder, a lever and link mechanism being provided whereby the pounder itself may be given relatively long travel as compared with short travel of the operating lever, the arrangement being such 40 that the movement of the cup or pounder will be rapid at the beginning of its downward stroke, when it encounters but little resistance, and much slower upon approaching the end of its stroke when greater power is 45 needed to compress the clothes owing to the resistance thereof.

An important object is also to provide a 50 device of this character provided with guide means connected with the cup and controlling the position thereof to effect tilting at the bottom of its stroke so that the imprisoned air 55 may bubble out or escape, thereby increasing the suction effect upon the upstroke.

Yet another object is to provide a device 55 of this character having the movable parts arranged in a certain peculiar relative man-

ner to insure the desired movements, adjustable spring means being, moreover, provided for assisting during the upstroke.

An additional object is to provide a device 60 of this character which will be simple and inexpensive to manufacture, easy to apply and use, positive in action, efficient and durable in service, and a general improvement in the art.

With the above and other objects and advantages in view, the invention preferably 65 consists in the arrangement and combination of parts and detailed structural features to be hereinafter more fully described and claimed, 70 and illustrated in the accompanying drawing in which:—

Figure 1 is a side elevation of the device 75 showing it arranged at the top of a tub prior to being clamped thereon and showing the normal position of the parts.

Figure 2 is an elevation showing the device 80 clamped in position and the operating lever moved to bring the pounder or cup to the lower limit of its movement, and

Figure 3 is a bottom plan view of the cup.

Referring more particularly to the drawing, the numeral 1 designates a bracket which is here shown as used in connection with a clamp 2 adapted to be engaged upon the upper edge of a tub A or other similar suitable receptacle. This clamp may be of any ordinary or preferred construction but it is here represented as having a depending tongue or lug 3 fitting within the tub, and an adjustable thumb screw or the like 4 adapted to engage against the outside of the tub. The clamp also carries or is formed with an upstanding trunnion 5 upon which the bracket member 1 is detachably and rotatably 85 mounted and this trunnion is preferably of sufficient length to project upwardly beyond the intermediate portion of the bracket, this projecting end carrying a collar 6 held in place by a removable pin 7, engageable 90 through a hole in the trunnion and a selected one of a plurality of holes 6^a located in different planes in the collar. The purpose of this feature is to permit taking up wear which may occur, it being desirable to prevent movement of the bracket along the trunnion. This arrangement also permits ready connection and disconnection.

Pivoted at 8 upon the upper end of the bracket member 1 is the main or operating 110 lever 9 which is intended to be of some length greater than the width of the tub upon which

the device is used and which preferably has its free end equipped with some suitable handle such as a rubber grip 10. While it is possibly immaterial, the lever 9 is represented as tubular in form for the sake of lightness.

Pivoted at 11 upon the lower end of the bracket 1 is an arm 12 to which is pivoted at 13 a link 14 in turn pivoted at 15 upon the lever 9. The distance between the pivot points 11 and 13 is considerably less than the distance between the pivot points 8 and 15 for a reason to be explained. It is preferable that the arm 12 be urged normally toward the lever 9 by a spring 16 which may be mounted in any preferred manner as for instance by having its ends engageable within holes 17 and 18 in the lever 9 and arm 12 respectively. A series of holes is provided in each of the arms so that by shifting the position of the spring the tension thereof may be varied. It is preferable that the holes be sealed with cork or the like 17^a to prevent ingress of water.

25 The arm 12 carries a pounder formed preferably as a substantially conical cup 19 which is open at its bottom and which has its top carrying one or more lugs 20 to which the arm 12 is pivoted as shown at 21. For maintaining the cup in proper position and guiding it during movement of the parts, I prefer to employ a rod 22 which is slidable through the lever 9 and rigidly secured to the cup in any desired manner as for instance by having its lower end connected with the center of a spider which may conveniently be formed of intersecting wires or the like 23 located at and secured in any desired manner to the open end of the cup.

30 In order to mount the device for use, the clamp 2 is engaged upon the edge of the tub A or the like and the screw 4 is tightened to maintain the proper holding action. Owing to the peculiar formation of the bracket 1 and its mounting upon the truncheon 5, it will be clear that the pivot points 8 and 11 are out of vertical alinement, the former being above but outwardly of the tub and the latter being below the top and spaced from the inner wall thereof. Initially the lever 9 will extend in a probably slightly inclined position and be spaced above the edge of the tub and the arm 12 carrying the cup 19 will be in its uppermost position. Whether the clothes to be washed, and the suds, are placed in the tub before or after the device is mounted in position is immaterial.

Assuming that the articles to be washed are in place, the operator grasps the lever 9 at the handle or grip 10 and forces the lever downwardly. The link 14 connected with the lever and with the arm 12 will operate to force the latter downwardly. It will be noted that at the top of the stroke air of course fills the cup. When the lever is forced

downwardly to bring the cup into forcible engagement with the clothes, the air is imprisoned and as the downward pressure is increased the air is compressed or there is, at least, a tendency to compress it which will 70 obviously result in causing the air to pass out through the clothes. When the cup reaches the bottom of the tub the clothes are positively squeezed while the action of the guide rod 22 will result in tipping the cup 75 slightly into the position shown in Figure 2 so that the remaining imprisoned air may bubble out and escape through the liquid. The down stroke having been completed, the operator moves the lever 9 upwardly, the 80 movement being greatly assisted by the spring 16 which tends always to swing the arm 12 upwardly. On this upstroke, there is a tendency to form a vacuum in the cup and the clothes are lifted to the surface of the 85 liquid where the vacuum is then broken so that the clothes will drop back into the tub. Quite naturally the alternate forcing of air through the clothes on the downstroke and sucking of suds through them on the upstroke will result in loosening the dirt so that the clothes will be very effectually cleansed.

Owing to the peculiar pivoting of the arm 12 with respect to the lever 9 and the location of the points 15 and 13 at which the link 14 is pivoted to the lever and arm it is clear that at the beginning of the downstroke the movement of the cup is rather rapid. This is desirable as it causes agitation of the suds and as no particular degree of power is needed to bring the cup into somewhat forcible engagement with the clothes. However, as the downward movement of the lever is continued the speed of the cup decreases on account of the pivot and link arrangement 105 above mentioned and as the speed decreases, the compressive power against the clothes increases proportionately while there is no change in the rate of movement of the lever. This is also highly desirable as a greater degree of power is needed to force the cup downwardly as it approaches the lower limit of its movement as the compressed clothes are, at this time, offering greater resistance.

Inasmuch as the bracket carrying all the 115 movable mechanism is pivoted upon the truncheon 5, the entire assembly may be swung horizontally so that the cup may be brought into action at different points between the opposite sides of the tub, all portions of the 120 clothes being thus acted upon.

From the foregoing description and a study of the drawings, it will be apparent that I have thus provided a simply constructed, inexpensive and easily operated device of the character specified which will efficiently perform all the functions for which it is intended and which may be manufactured and sold as a complete and separate entity capable of employment in con- 130

nection with any ordinary tub or other similar receptacle, no special equipment being needed.

While I have shown and described a preferred embodiment of the invention, it should be understood that I reserve the right to make such changes in the form, construction and arrangement of parts as will not depart from the spirit of the invention or the scope of the subjoined claims.

Having thus described the invention, I claim:—

1. A pounder washer comprising a support adapted to be mounted upon a receptacle, an actuating lever terminally pivoted to said support for vertical swinging movement, an arm terminally pivoted to the support for vertical movement, a link pivotally connected with the lever and the arm near their pivoted ends and at unequal distances from the pivots thereof, and a pounder cap carried by the arm.

2. A pounder washer comprising a support adapted to be mounted upon a receptacle, an actuating lever pivoted to said support for vertical swinging movement, an arm pivoted to the support for vertical movement, a link pivotally connected with the lever and the arm at unequal distances from the pivots thereof, a pounder cup carried by the arm, and means carried by the cup and engaging the lever for guiding the cup during its movement.

3. A pounder washer comprising a support adapted to be mounted upon a receptacle, an actuating lever pivoted to said support for vertical swinging movement, an arm pivoted to the support for vertical movement, a link pivotally connected with the lever and the arm at unequal distances from the pivots thereof, a pounder cup carried by the arm, and means carried by the cup and engaging the lever for guiding the cup during its movement, comprising a rod rigid with respect to the cup and slidale through the lever.

4. In a clothes pounder of the character described, a supporting member adapted to

be clamped upon the edge of a receptacle, a bracket carried by said supporting member, an actuating lever pivoted on one end of said bracket for movement in a vertical direction, an arm pivoted on the other end of the bracket, the pivot points of the arm and lever being out of vertical alinement, a cup carried by the arm, and link means pivotally connected with the lever and the arm, the distance between the pivot point of the arm and the pivotal connection of the link means therewith being less than the distance between the pivot point of the lever and the point of connection of the link means therewith.

5. In a device of the character described, a supporting member adapted to be mounted on a receptacle, a bracket carried by said supporting member and arranged at an incline with respect to the vertical, an actuating lever pivotally connected with the upper end of the bracket, an arm pivotally connected with the lower end of the bracket, means connecting the arm and lever for simultaneous movement at different speeds, a cup pivotally carried by the arm, and guide means rigidly carried by the cup and slidably engaging the lever for effecting tilting of the cup.

6. In a device of the character described, a supporting member adapted to be engaged upon a receptacle and having an upstanding trunnion, a bracket rotatably and detachably mounted upon said trunnion, a lever operated pounder carried by the bracket, said trunnion projecting upwardly beyond the bracket and having a transverse hole therein, a collar on the projecting end of the trunnion having a plurality of radial holes therein located in different horizontal planes any one of which is adapted to be brought into registration with the hole in the trunnion, and a securing element passing through the registering holes.

In testimony, that I claim the foregoing as my own, I have hereto affixed my signature.

CHARLES HERBERT CANFIELD.
